(57) **CLAIM**

The ornamental design for a gas stove structure as shown and described.

DESCRIPTION

FIG. 1 is a perspective view of a gas stove structure showing my new design;

FIG. 2 is a front elevational view of the gas stove structure;

FIG. 3 is a rear elevational view of the gas stove structure;

FIG. 4 is a left side elevational view of the gas stove structure;

FIG. 5 is a right side elevational view of the gas stove structure;

FIG. 6 is a top plan view of the gas stove structure; and,

FIG. 7 is a bottom plan view of the gas stove structure.

The broken lines show portions of the gas stove structure and form no part of the claimed design.
